UNITED STATES PATENT OFFICE

JOHN W. PERRY, OF WHEELING, WEST VIRGINIA

TIN-PACK-HANDLING MECHANISM FOR HEATING FURNACES

Application filed September 8, 1928. Serial No. 304,626.

The invention generally has for its object to provide a tin-pack heating furnace wherein is provided means for conveniently and efficiently handling and conveying the packs into and through the heating chamber in a manner insuring proper thorough heating thereof preparatory to final rolling.

In its more detailed nature the invention seeks to provide an improved conveyor mechanism for receiving the tin, black plate, or sheet iron pack as they leave the doubler and conveying them through the furnace, automatically handling the packs so as to assure proper thorough heating of the same as they pass through the furnace.

With the above and numerous other objects in view as will appear as the description proceeds, the invention resides in certain novel features of construction, and in the combination and arrangement of parts as will be hereinafter more fully described and claimed.

In the drawing:

Figure 1 is a diagrammatic plan view of the apparatus embodying the features of my invention showing the furnace in horizontal section,

Figure 2 is a longitudinal vertical section through the furnace showing the output conveyor,

Figure 3 is a similar section showing the take in conveyor,

Figure 4 is an enlarged detail vertical transverse section taken substantially on the line 4-4 of Figure 1,

Figure 5 is a similar section taken substantially on the line 5-5 of Figure 1,

Figure 6 is a detail vertical transverse section taken substantially on the line 6-6 of Figure 1,

Figure 7 is a vertical detail transverse section taken substantially on the line 7-7 of Figure 1,

Figure 8 is a detail vertical section taken substantially on the line 8-8 of Figure 1,

Figure 9 is a detail vertical transverse section taken substantially on the line 9-9 of Figure 1,

Figure 10 is a longitudinal vertical detail section taken substantially on the line 10-10 of Figure 1,

Figure 11 is a fragmentary diagrammatic plan view at the output end of a modified form of the invention,

Figures 12 and 13 are sectional views taken substantially on the lines 12-12 and 13-13 respectively of Figure 11,

Figure 14 is an enlarged detail section showing the flipper operating mechanism for this modification, and

Figure 15 is a detail section taken substantially on the line 15-15 of Figure 1.

Referring to the drawing in detail, in which like numerals of reference indicate like parts in all of the figures, 1 indicates the walls of a heating furnace which may be constructed in the usual manner of fire brick, steel beam supported and said walls enclose a heating chamber 2 which is to be kept heated to the desired temperature by any approved heating unit (not shown).

At one end of the furnace there is provided an intake passage 3 alongside of which is an offtake passage 4. Capped supports 5 are provided at the entrance of the intake passage 3 and one of them is provided with an electric switch button 6 so that when a pack is placed thereon a circuit (not shown) will be closed for lighting an incandescent bulb 8 located at the rolling mill 9 so as to signal an operator that a pack has been placed upon the support 5 so that said operator may start the machinery as will be hereinafter more clearly described.

A shaft 10 is suitably supported for rotation outside of the passages 3 and 4. This shaft 10 is embedded in a platform 11 forming a continuation of the bottom 12 of the furnace as is clearly disclosed in Figures 2 and 3.

The bottom 12 of the furnace is provided with a passage 14 continuing a distance into the platform 11 having an opening 15 in the furnace and an opening 16 in the platform exteriorly of the furnace.

The shaft 10 is journaled in the platform to extend across the passage 14 below the opening 16. A sprocket 17 is mounted on this shaft 10. A shaft 18 is journaled in the bottom 12 at the inner end of the passage 14 and has a sprocket 19 thereon.

A chain 20 is trained over the sprockets 17 and 19 and has a plurality of spaced projections or teeth 21 thereon. This chain extends between the supports 5 as is clearly illustrated in Figure 1.

The upper run of the chain is disposed on top of the bottom 12 and the platform 11 while the lower run of the chain is in the passage 14. The upper run of the chain passes through the intake passage 3.

A door 22 is swingably mounted as at 23 in the intake passage 3 and will swing partially open as a pack passes by, by the pack engaging therewith. The distance between the teeth is such as to accommodate packs therebetween as is clearly illustrated in Figure 3. A shaft 24 is journaled above the platform and has a gear 25 thereon meshing with a gear 26 on the shaft 10, as shown to advantage in Figure 10.

The gear 25 is loose on the shaft 24 and has a clutch 27 associated therewith so that said clutch may be closed to cause the rotation of the gear 25 with the shaft 24. This clutch 27 is conveniently located adjacent the incandescent bulb 8 by means of a lever 28, link 29, bell crank 30, link 31, and lever 32 or in any other preferred or suitable manner.

The bottom 2 of the furnace is provided with another passage 33 similar to passage 14 and in spaced parallelism thereto and this passage is provided with end openings 34 and 35.

A shaft 36 is at one end of the passage 33 and has a sprocket 37 thereon. A shaft 38 is at the other end of the passage and has a sprocket 39 thereon. The shaft 38 is operatively connected with the shaft 24 by means of chain and sprocket mechanism 40 so that the chain 41 trained about the sprockets 37 and 39 moves in an opposite direction from the chain 20.

This chain 41 has teeth 42 thereon similar to teeth 21 for receiving packs therebetween as clearly illustrated in Figure 2.

The chain 41 is wholly disposed within the furnace. The off take passage 4 has hingedly mounted therein a door 43 which will be open by the packs as they pass off out through this passage 4 as will be more apparent as the description proceeds.

A guide strip 44 is disposed equidistant between the chains 20 and 41 and rises from the bottom as is clearly illustrated in Figure 5 so that the packs will be guided between the side walls of the furnace and this strip when moved by the chain.

The numeral 45 denotes an electric motor geared as at 46 with a shaft 47. This shaft 47 is geared as at 48 to the shaft 24.

Supports 49 are provided adjacent the rolling mill 9 and conveyor chains 50 lead therefrom through passage 4 into the off take side of the furnace. These chains 50 are

similar in construction to chains 20 and 41 and are actuated by a shaft 51 and a chain and sprocket mechanism 52 which has a clutch structure 53 operatively connecting it with a shaft 54 that is operatively connected by a chain and sprocket mechanism 55 with the shaft 24 and the clutch 53 is actuated by a lever 56 adjacent lever 28, link 57 and lever 58.

Two rows of upstanding guide rollers or knobs 59 are provided alongside the chains 50.

The bottom 12 is provided with one or more transverse channels 60 in the upper surface thereof at the end of the chain 20 and pusher blocks 61 are movable therein actuatable by rods 62.

These rods 62 have pin and slot connections 63 with a crank 64 on a shaft 65 journaled in bearings 66 in a pit 67. The shaft 65 is rocked by a crank 68, rod 69 and eccentric 70 having a clutch connection 71 with shaft 47.

Obviously when the shaft 47 is rotating and the clutch 71 is in said eccentric will push the connecting rod 69 to cause the rocking of shaft 65 thus causing the pusher block 61 to move outwardly in the channels 60, for shoving a pack which has been deposited by the chain 20 over the channels on to the chain 41.

Sometimes it is desirable to flip the packs over as they are transferred from the chain 20 to the chain 41 and are provided with a special flipping mechanism which comprises flipper fingers 73 in recesses 74 formed in the upper surface of the bottom 12 and rockable adjacent their ends as at 75 and pivotally connected with rods 76 operable by eccentrics 77 on the shaft 47, the eccentrics 77 having a clutch connection 78 with the shaft 47 so that when this clutch 78 is in the fingers will be rocked upwardly and over to flip the pack over on to the chain 41 from the chain 20.

A bar 80 is slidable in suitable brackets 81 to the outside of the furnace and is held in either of two positions by a spring 82 having keeper notches 83 to receive a lug 84 on the bar 80.

Rigid arms 85 project from this bar 80 to engage disks 86 slidable on the shaft 47 and rotatable therewith and connected with the clutches 71 and 78. Springs 87 are associated with these disks to normally hold the clutches in.

These arms 85 extend through guide plates 89 having guide slots 90 therein for this purpose. As shown in Figure 1 it will be seen that by moving the bar 80 to the left clutch 71 may be disengaged.

By moving the bar 80 to the right clutch 78 will be engaged as will also clutch 71 but the pusher mechanism will not interfere with the operation of the flipper. That is when the flipper mechanism operates the pusher mechanism also operates but is ineffective.

since the flipper mechanism will lift the pack up out of the way of the blocks 61.

The arms 85 are only rigid in respect to the bar 80 as far as horizontal swinging is concerned since as will be seen in Figure 7 these arms 85 are pivoted as at 90 with cranks 91 depending from the bar 80 and this bar 80 may be slightly rocked by an arm 92 of angular construction which extends in 10 through an opening 93 in the bottom to be engaged by one of the teeth on the chain 20.

When a tooth engages this arm 92 it will cause the slight rocking of the bar 80 which will cause an outward push on the arms 85 15 against the tensions of springs 94 so as to place the ends of these arms in the paths of movement of the cams 95 on the disks 86, so that the disks will be moved to the left of Figure 1 to disengage their respective 20 clutches 71 and 78.

It will be noted from an inspection of Figures 4 and 5 that the upper runs of chains 20, 41 and 51 move in channels so as to be flush with the upper surface of the bottom 25 of the surface and the platform and the teeth project above the bottom of the furnace and the platform.

In using this apparatus an operator takes the pack from the doubler and places it on 30 the support 5 thus signalling the other operator at the control levers 28 and 56.

The operator adjacent the control levers then pulls the lever 28 causing the rotation 35 of gear 25 and chain and sprocket mechanism 40 so as to cause the movement of the chains 20 and 41 as heretofore explained so that the pack will be drawn into the furnace.

This operation is continued until a pack is deposited over the channel 60 so that the 40 pack may be pushed over or flipped over on to the chain 41, the pusher and flipper mechanism being controlled in proper timed relation by the teeth engaging the arm 92 as heretofore explained.

45 When the pack moves to the output passage 4 it is deposited on the chain 50 and by proper manipulation of these chains is deposited on the supports 49, these chains 50 being controllable through clutch 53.

50 Thus every time the bulb 8 lights the operator throws in the clutch 27 and eventually every time this clutch is thrown in a pack will be ejected from the furnace and these ejected packs may be drawn to the 55 supports 29 to be engaged in the rolling mill 9 in the usual well known manner.

Sometimes it is not possible to place the rolling mill opposite the output passage of the furnace and by referring to Figure 11 60 it will be seen that I have devised a means for moving the packs transversely.

The numerals 100 denote chains trained over sprockets on shafts 101 and 102. The sprockets are rotatable together by sleeves 65 108 on the shafts 101 and 102 and one of

these sprocket units has a clutch structure 104 associated therewith and with the shaft 102.

This clutch is actuated by a lever 105 and a link 106. Chains 107 are trained over 70 sprockets on shaft 108 which is operatively associated with the shaft 102 through gearing 109 and clutch 110.

The clutch 110 is operated by a lever 111 and a link 112. The shaft 102 is rotatable 75 by an electric motor 114. Thus the chains 107 would receive the pack from the chains 50 and lead the packs on to the chains 100 or vice versa.

In the example mentioned where the pack 80 goes from the chains 107 to the chains 100 I have provided a flipping mechanism which may be used when desired consisting of a shaft 115 and having fingers 116 thereon. This shaft 115 is rocked by means of a crank 85 117, a link 118 and a lever 119.

It is thought that the construction, operation, utility and advantages of the invention will now be quite apparent to those skilled in this art without a more detailed description thereof.

The present embodiments of the invention have been disclosed in detail merely for the purposes of exemplification since in actual practice they attain the features of advantage 95 enumerated as desirable in the statement of the invention and the above description.

It will be apparent that changes in the details of construction, and in the combination and arrangement of parts may be resorted to without departing from the spirit or scope of the invention as hereinafter claimed or sacrificing any of its advantages.

Having thus described my invention, what 105 I claim as new is:

1. In combination, a heating furnace including a bottom, a pair of endless conveyor chains mounted in the bottom running alongside of each other in opposite direction, said bottom having channels at the end of one of said chains, said channels being disposed transversely of said one chain, pusher blocks operable in the channels to push the packs from said one chain over to the other chain, 110 rods connected with said pusher blocks, a shaft, eccentric means on the shaft to operate the rods, flipping fingers disposed adjacent the pusher block, rods connected with said flipping fingers, additional eccentric 115 means on said shaft to operate the last mentioned rods, and a clutch mechanism for controlling each of said eccentrics whereby the pusher blocks and flipping fingers may be operated simultaneously or the flipping 120 fingers may be rendered inoperative.

2. In combination, a heating furnace, a pair of conveyors alongside each other, means for transferring packs from one conveyor to the other, said means embodying a flip- 125

ping mechanism and a pusher mechanism, one of said conveyors having teeth, means actuatable by said teeth for holding the flipper mechanism inoperative, said last mentioned 5 means comprising an arm engageable by the teeth, a bar rockable by the arm, a second arm, a crank on the bar pivotally engaged with the last mentioned arm, means for slidably mounting the bar so that when the bar 10 is rocked said last mentioned arm is pushed, a clutch mechanism for controlling said pusher mechanism and said flipper mechanism, said clutch mechanism including a disk having a cam thereon and into the path of 15 movement of which the last mentioned arm will be pushed when the first mentioned arm is actuated by one of the teeth on one of the conveyors.

3. In combination, a heating furnace, a 20 pair of conveyors alongside each other, means for transferring the packs from one conveyor to the other, said means comprising a pushing mechanism and a flipper mechanism, means for controlling the said mechanisms, said means embodying a clutch mechanism, one of said conveyors having teeth, and means actuatable by the teeth for controlling the clutch mechanism.

In testimony whereof I affix my signature.
JOHN W. PERRY.
